(57) **CLAIM**

The ornamental design for a shopping cart, shown and described.

DESCRIPTION

FIG. 1 is an isometric view of a shopping cart showing our design;

FIG. 2 is a front end view thereof, as taken from the left end of FIG. 1;

FIG. 3 is a rear end view thereof, as taken from the right end of FIG. 1;

FIG. 4 is a right side view thereof;

FIG. 5 is a left side view thereof (the side views are mirror images of one another);

FIG. 6 is a top view thereof; and,

FIG. 7 is a bottom view thereof.

The cross-hatching shading is fragmentarily shown for convenience of illustration, it being understood that the cross-hatching is uniformly continued over the surface on which it appears.
